REFLUX EAR NOZZLE

John J. Nowak, Buffalo, N. Y.

Application February 16, 1938, Serial No. 190,871

5 Claims. (Cl. 128—240)

This invention belongs to the class of reflux nozzles and it relates particularly to an aural nozzle for establishing a flow of medicated vapor or the like through the passages of the outer ear.

One of the objects of the invention is to provide an ear nozzle comprising a tubular member, one end of which is adapted to be inserted into the ear and having a removable partition so constructed and arranged as to divide the tubular member into serial passages.

Another object of the invention is the provision of an ear nozzle, the component parts of which are capable of being individually detached or removed to provide for the easy and complete sterilization or cleansing of the entire nozzle.

Other objects of the invention will appear as the following description of a preferred and practical embodiment of the invention proceeds.

In the drawing which accompanies and forms a part of the following specification and throughout the several figures of which the same characters of reference have been employed to designate identical parts :

Figure 1 is a view in elevation of a head set embodying a pair of the aural nozzles constituting the subject of the present invention;

Figure 2 is a longitudinal section through one 30 of the nozzles;

Figure 3 is a cross section taken along the line 3—3 of Figure 2; and

Figure 4 is a cross section taken along the line 4—4 of Figure 2.

The treatment of the ear, as contemplated, in the present invention involves the application of a current or flow of medicated vapor from a suitable source for such vapor, into contact with the surfaces of the cavities or passages of the outer ear. In order to establish such circulation it is essential that the ear passages be vented so as to displace the inert air therein contained by the medicated vapor, and to apply a continuous current of fresh medicated vapor to the surfaces during the period of treatment.

With this end in view the invention involves the employment of a head set consisting of a resilient strap 1 adapted to encircle the head and having the ball joints 2 and 3 at its opposite sides from which depend the clamp links 4 and 5 which in turn embrace the ball ends 6 and 7 which form a part of the ear nozzles per se constituting the subject of the present invention. The medicated vapor is led to the nozzles 8 and

9 from a source not shown, through the flexible tubes 10 and 11.

The ear nozzles each comprise a block or body 12 having a transverse bore 13 therethrough. This bore forms a seat for a cylindrical tube 14 which is slidably and freely inserted through said bore. The tube 14 is secured in place by a set screw 15 threaded into the block or body 12 and the lower end of which bears against the tube 14. The upper end of the set screw 15 carries the ball ends 6 or 7.

The tube 14 is open at both ends and preferably has its inner end 16 slightly reduced and rounded as shown so that it can be comfortably inserted into the ear. The tube 14 is preferably of uniform and smooth internal diameter throughout excepting at its extreme inner end so that it can be readily cleansed of any condensation or other residue of the medicated vapor.

The tube 14 is divided into passages 17 and 18 by a preferably thin and flat partition 19 which is insertable from the outer end of the tube 14 and extends throughout its length, preferably terminating at the extreme inner end of the tube 14 as shown. The partition 19 is suitably secured to a handle 20. In the preferred form of the invention the handle is provided with a semi-cylindrical extension 21 having a flat upper surface 22 to which the partition 19 is secured by means such as the screw 23. The semi-cylindrical extension 21 fits into the outer end of the tube 14 forming a closure for the outer end of the passage 18 defined by the partition 19. The block or body 12 has an opening 24 which registers with an opening 25 in the tube 14 communicating with the passage 18 when the tube 14 is properly in place. The outer end 26 of the passage 17 is left open.

A nipple 27 is screwed into the block or body 12, the bore of which nipple communicates with the opening 24, and the flexible tube 10 or 11 is slipped over said nipple. In operation, when the inner end 16 of the aural nozzle is inserted into the ear, medicated vapor flows by way of the nipple 27, openings 24 and 25 into the passage 18, through the cavities of the outer ear, through the passage 17, and discharges by way of the open outer end of the passage 17.

The particular virtue of this aural nozzle is that the component parts may all be readily separated one from the other for purpose of sterilizing or cleansing the apparatus. This is quite necessary for the medicaments customarily employed are heavy volatile vapors which may

condense on the walls of the various conduits of the nozzles through which the vapor passes.

In order to disassemble the device, it is necessary merely to pull upon the handle 20, the extension 21 and partition 19 being thus readily removed leaving the interior of the tube 14 an unobstructed smooth cylindrical surface. The tube 14 may be withdrawn from the block or body 12 by slightly unscrewing the set screw 15 which may readily be done by means of the fingers. The only other removable part, the nipple 27, may be unscrewed if desired. The parts thus separated may be put into a suitable vessel and sterilized.

15 It is contemplated that the aural nozzle may be made of either metal or any other suitable material, a non-metallic substance being preferred on account of the fact that it will not give a sense of uncomfortable coldness to the 20 patient when the nozzle is inserted into the ear and from the further fact that there will be less condensation upon a non-metallic surface than upon metallic members.

While I have in the above description disclosed 25 what I believe to be a preferred and practical embodiment of the invention, it will be understood to those skilled in the art that the specific details of construction as shown and described are merely by way of example and not to be construed as limiting the scope of the invention as 30 set forth in the appended claims.

What I claim is:

1. Reflent ear nozzle comprising a tube open 35 at both ends having the inner end adapted to enter the ear, a removable partition insertable in the outer end of said tube and extending therethrough, a plug on one side of said partition closing the outer end of one of the passages defined by said partition, and a connection from 40 a source of vapor communicating with said passage.

2. Reflent ear nozzle comprising a tube open at both ends, having the inner end adapted to enter the ear, a removable partition insertable

in the outer end of said tube and extending therethrough substantially to the inner end, a plug on one side of said partition closing the outer end of one of the passages defined by said partition, the adjacent end of the other passage being left open, and the ends of said passages at the inner end of said tube being in open communication with the ear cavity and with each other, and a connection from a source of vapor communicating with the passage and the closed outer end whereby a serial path for vapor flow is provided through said passages and the cavity of the ear.

3. Reflent ear nozzle comprising a tube open at both ends, having the inner end shaped to 15 comfortably enter the ear, a removable partition insertable in the outer end of said tube and extending through said tube, dividing the latter into passages, a handle to which said partition is secured, said handle having an extension fitting and closing the outer end of one of said 20 passages when said partition is in fully inserted position, and a connection from a source of vapor communicating with said passage.

4. Reflent ear nozzle consisting of a body 25 member having a through bore and an intersecting bore, a tube open at both both ends removably inserted through the through bore in said body member, a removable partition insertable in the outer end of said tube and extending therethrough, a plug on one side of said partition at one end thereof closing the outer end of one of the passages defined by said partition, and a connection from a source of vapor 30 communicating with said plugged passage of the 35 tube through registering bores in said body and tube.

5. Reflent ear nozzle as claimed in claim 4, with a set screw for securing said tube in said body, the outer end of said set screw being formed 40 with a joint element for connecting said nozzle to a head set.

JOHN J. NOWAK.
